COMPOSITION DOOR

Robert L. Davison, New York, N. Y., assignor to
 John B. Pierce Foundation, New York, N. Y., a
 corporation of New York

Application December 20, 1932, Serial No. 648,135

1 Claim. (Cl. 20—35)

My present invention relates to building construction and more particularly to an improved type of door.

5 A feature of my invention is the production of a door as a unitary structure.

A feature of my invention is the production of a relatively sound-proof door composed of a plurality of different kinds of material united into a unitary structure.

10 A feature of my invention is the production of a unitary sound-proof door in which the pivoting members are formed as an integral part of the door structure.

15 A feature of my invention is a relatively sound-proof door comprising a core of high sound and heat insulating qualities, hermetically encased in an enclosing shell.

20 A feature of my invention is an improved heat-insulating door or similar structure by hermetically encasing a core of material having high insulating qualities as regards heat and sound, the encasing material being molded into shape under the influence of heat and pressure.

25 In the accompanying drawings illustrating a preferred embodiment of my invention and the method by which the same is made,

Fig. 1 is a section through a door structure or panel of any desired size;

Fig. 2 is a fragmentary view of one of the 30 corners of a panel, such as is shown in Fig. 1, and with the enclosing material on one face thereof removed;

Fig. 3 is a perspective view showing the lower end of a door or panel and showing the constructional details thereof;

Fig. 4 is a fragmentary view partly in section showing the upper corner of a panel or door and illustrating the method of forming the pivotal hardware integral therewith;

40 Fig. 5 is a fragmentary view in section of the lower corner of a door or panel and showing a pintle mounting means formed integral therewith;

Fig. 6 is a bottom plan view of Fig. 5; and

45 Fig. 7 is a sectional elevation showing a press and illustrating the method of manufacture of my improved door or panel.

Referring to the drawings, there is shown a core 10 of relatively high insulating properties as 50 regards heat and sound, such core 10 being of any desired shape and thickness, the outer contour following closely but being smaller than the contour of the door or panel desired to be formed, and having a thickness less than the finished 55 thickness of the door or panel. Such core 10 is

encased in a shell of moldable material, any material of this character being suitable and preferably such material is one having high resistance to abrasion, practically immune from warping, and resistant to acids, alkalies and the like.

The casing is composed of what may be termed a border 11 extending completely about the periphery of the core 10 and formed integral with the molding 11, and covering each face of the core 10 are plates 12. It is understood of course that the molding 11 and plates 12 are formed of the same material and are molded into an integral structure, so that the core 10 is hermetically encased therein. By reference to Fig. 2, the method in which the said molding is folded about 10 a corner of the core 10 is readily apparent.

As stated above, the door or panel may be of any size or shape as regards peripheral outline and thickness, and when utilized as a door, it is sometimes desirable to have the pivot hardware 20 formed integral with the door structure. In such event and referring to Fig. 4, it will be seen that the core 10 at the places where the hinge plate 13 is to be attached is cut away as indicated by the reference numeral 14, after which the hinge member 13 is placed in position and held in position with respect to the door under construction, and when the moldable material 11 is subjected to heat and pressure, such moldable material will 25 flow in and around the portion of the hinge 13 within the limits of the structure under construction, and such material 11 will flow through the holes 15 to positively hold the hinge member 13 in position.

It may sometimes happen that a door adapted 35 to be swung on pintles is employed, and in this case the upper and lower corners of the door structure have the core 10 thereof cut away and excess material 11 is placed in this cut away portion, and in molding a metal or other pin 16 is 40 held in the mold and the mold is so formed as to make the portion of the molding 11 thicker than the portion surrounding the hole made by the pin 16 than in the ordinary form of door. Such construction may be apparent from a study of 45 Figs. 5 and 6.

The panel or door is molded at a single operation and when in completed form, the insulating material 10 is hermetically sealed in a casing of the moldable material. Any material which will 50 flow under the influence of heat and pressure may be employed, and such material may be any resin compound or any compound such as "Bakelite" and the like, but preferably I use the material known as "Vinolyte", which in addition to the 55

property of flowing under the influence of heat and pressure has the further additional property of being non-warping after the molding operation has taken place.

- 5 In carrying out the method of making panels or doors under my present invention, I preferably utilize a press consisting of a platen or base 17 in which the upper face is cut away to appropriate size as regards outline and depth of the required 10 finished panel or door, as indicated by the reference numeral 18. I also provide vent holes, as the vent holes 19, through which gases driven out of the moldable material and out of the insulating material 10 may flow and thus avoid the danger of blow-holes.
- Also, I provide a means for rapidly heating or 15 cooling the platen 17. I may do this by forming in the body of the platen 17 a plurality of parallelly arranged and interconnected passages 20 all connected to a pipe 21 which may, as is usual, 20 be connected to a source of steam under pressure or to a source of cold water or other liquid. In place of the passages 20 in the material of the platen 17, I may make the bottom face of the 25 platen 17 relatively thin and have the same rest in a flat coil which will be the equivalent of the plurality of parallelly arranged and interconnected pipes 20. Associated with the platen 17 is a plunger 22 which has a peripheral contour 30 similar to the contour of the opening 18 in the upper face of the platen 17.

Means are also provided in the platen 17 for either rapidly heating or cooling the same as by the forming of a plurality of interconnected pipes 35 23 therein, all connected to a pipe 24, which in turn is connected to means for attaching the same to a source of steam under pressure or to a source of cold water or other cooling liquid.

In the process of forming my improved panel 40 or door, I utilize sheets or plates 25 of the material to form the molding 11 and face plates 12, and such material is utilized until the entire surface of the bottom of the cut away portion 18 is entirely covered; to provide for the filling of the 45 interstices between such plates 25, I may sift or place powder formed of the material 25 in order to make an even layer of the material over the bottom of the opening 18.

On top of the plates 25 is carefully arranged a 50 core 10 of the desired thickness and of a peripheral size less than the peripheral size of the opening 18, this being necessary to provide the end thicknesses or molding 11, referred to in connection with Figs. 1 and 2. After the core 10 is in 55 position, the molding 11 is placed in position as shown in Fig. 7, and the space not taken up by either the molding 11 or core 10 is filled with the powdered material 26. Afterwards, the molding 11 and top face of the core 10 are covered with 60 plates 25 and the interstices between such plates 25 filled with the powdered material 26.

The plunger 22 is then placed in position, as 65 shown in Fig. 7, and the whole placed in a press and the structure subjected to heat and pressure. The volumetric displacement of the core 10 before the pressing operation is of course greater than the desired finished volumetric displacement, and such displacement can be readily calculated to any degree desired.

70 The pressure and heating are continued until the moldable material within the cavity 18 of the

platen 17 flows, and such flowing of the material will cause the plates 25 and molding 11 to flow into a homogeneous mass.

During the operation of subjecting the structure to pressure, any moisture within the core 10 will be forced out and will be driven through the perforations 19 in the platen 17. The structure to be manufactured is, after the moldable material has begun to flow, held under heat and pressure for a period of approximately five minutes, although more or less time may be consumed if desired.

While the pressure is maintained after this period, the heat is removed from the heating devices and cold water substituted therefor, 19 which has the effect of rapidly chilling both the platen 17 and the plunger 22 and thus facilitates rapidity of construction.

In addition, the sudden chilling of the platen and plunger imparts a relatively high finish to 21 the outer surface of the enclosing material, this being particularly so if the surfaces of the platen and plunger in engagement with the moldable material are in themselves highly polished.

Also, the sudden chilling of the platen and 25 plunger enables the resulting panel or door to acquire a permanent set and it has been found that after such permanent set has taken place, that the panel or door will not be subject to warping.

While I have necessarily described the preferred embodiment of my invention and the method by which the same is produced somewhat in detail, it is to be understood that I may vary the size, shape and arrangement of parts comprising the devices and the various steps in the process of producing the same within relatively wide limits without departing from the spirit of the invention.

Also, while I have described the mold by means 40 of which the panel is fabricated into commercial shape as being composed of a platen having associated therewith a plunger, it is to be understood that this is merely one showing of a suitable device of this character, and obviously, I may 45 utilize a mold having a peripheral band to define the limits of the area of the desired panel and have associated therewith a pair of plungers operated simultaneously and by any desired means, so as to move toward each other under 50 pressure.

Or, the device shown in Fig. 7 may be such that the plunger and the platen are independently mounted and movable relatively toward each other.

I claim:

An integral door unit comprising a mass of insulating material, molded material wholly enveloping said mass of insulating material, the peripheral edges of said molded material serving as the peripheral edges of the door being substantially thicker than the thickness of said mass of insulating material, said molded material being provided with an additional quantity along one edge, and a hinge member embedded in said additional quantity whereby said insulating material, said enveloping molding material and said hinge member form an integral door unit, said hinge member projecting beyond said edge of said molded material.

ROBERT L. DAVISON.
